APERTURED CUTTING PLATE FOR
DRY-SHAVING DEVICES

Wilhelmus Lambertus Leonardus Vivie, Eindhoven, Netherlands, assignor, by mesne assignments, to Hartford National Bank and Trust Company, Hartford, Conn., as trustee

Application May 3, 1946, Serial No. 667,025
In the Netherlands March 14, 1942

Section 1, Public Law 690, August 8, 1946
Patent expires March 14, 1962

2 Claims. (Cl. 30—43)

1

This invention relates to an apertured cutting plate of substantially flat shape intended for a dry-shaving device and also to a dry-shaving device comprising such a cutting plate.

According to the invention the cutting plate is provided on the outside to be applied to the skin with one or more reinforcement ribs extending from the flat surface and tightly bulging the skin, said ribs being supported at at least one of the ends.

Due to the skin-bulging effect of the reinforcement ribs the hairs thus erected to a greater degree and extending more outwardly are more readily conducted into the apertures of the cutting plate and are severed as short as possible by the cutting member moving behind it, the reinforcement ribs also avoiding detrimental sag of the flexible cutting plate which by itself is very and constructed to be flat.

Indeed, sagging of the cutting plate which may be due to the pressure of the skin results in that the cutting member no longer sufficiently engages the contact surface of the cutting plate at all points and thus during shaving gives rise to the sensation as if the hairs were pulled.

Particularly if use is made of a rotary cutting plate sagging of the cutting plate may be due to the cutting plate being set vibrating, a kind of resonance phenomenon which apart from the said defect of unsatisfactory engagement of the cutting member may even result in that the material between the apertures of the cutting plate cracks and breaks off.

The invention also remedies this defect.

The invention is therefore particularly efficient in the case of cutting plates having slits formed in them, because the small dams located between the slits are more subject to the said kinds of sagging than the material of cutting plates in which for example circular or oval-shaped apertures are formed. In this case the bulging and reinforcing ribs are preferably constituted by several small dams normally provided between the slits of identical width, if desired, but of larger thickness than the other small dams and the reinforcement ribs may be supported at both ends. By identical width of the dams reduction of the shaving surface due to the presence of the bulging and reinforcing ribs is avoided as far as possible.

If the invention is applied to a cutting plate for a dry-shaving device which comprises a cutting member and in which the cutting plate is provided with an annular contact surface for the said cutting member and a central story of rigid construction and also with slits extending radially

2

to the outer edge of the cutting plate, the bulging and reinforcing ribs are supported, according to the invention, at one end by the central story and at the other by the outer wall of the cutting plate.

The thickness of the bulging and reinforcing ribs is preferably approximately from 0.2 to 0.8 mm.

In order that the invention may be clearly understood and readily carried into effect it will now be described more fully with reference to the accompanying drawing, in which some few diagrammatically shown embodiments are illustrated.

Fig. 1 shows a side elevation of a cutting plate according to my invention.

Figs. 1-a shows a plan view of the cutting plate of Fig. 1.

Fig. 1-b shows a cross-sectional view of the cutting plate of Fig. 1 together with an associated cutting member.

Fig. 2 shows a plan view of a cutting plate of rectangular shape according to my invention.

Fig. 2-a shows a cross-sectional view of the cutting plate of Fig. 2.

Fig. 3 shows a plan view of an annular cutting plate with a central recess according to my invention.

Fig. 3-a is a cross-sectional view of the cutting plate and associated cutting member of Fig. 3.

Referring to the drawings, Fig. 1-b shows a cutting plate 2 having formed in it circular apertures 1 jointly with a rotary cutter 3. According to the invention the outside to be applied to the skin is provided with one or more ribs 4 extending from the flat surface and tightly bulging the skin and also serving for reinforcement of the cutting plate as shown by Fig. 1-a, said ribs being supported at at least one of the ends so that sufficiently rigid rib construction is ensured. In the example shown the reinforcement ribs merge at 5 into the cylindrical outer wall 6 of the cutting plate 2.

The side elevation of Figure 1 lastly illustrates the skin-tightly bulging effect of the ribs. In the bends 8 the hairs are more expulsed outwardly from the skin pores by the tight bulging and in addition more erected so as to permit of their being captured more readily in the apertures. This therefore also results in an improved shaving effect. The reinforcement ribs in addition avoid harmful sagging of the cutting plate so that during shaving a more satisfactory engagement of the cutting edges of the cutting member is ensured throughout the length. This also results in quicker and shorter cutting of the hairs.

Referring to Figure 2 the invention is applied to a cutting plate of rectangular shape. For the sake of simplicity identical members are designated by like reference numerals. Instead of circular apertures use is, however, made of long slits 9 in the present case. The reinforcement ribs are supported at both ends. As certain well-known cutting plates of this shape are always provided with a reinforcement rib 10 at each of the two ends of the cutting plate, even a single centrally arranged bulging and reinforcing rib according to the invention may yield the desired effect in those cases in which the length of the cutting plate is not excessive.

In the present case the width of the reinforcement ribs is equal to the width of the dams 11 provided between the slits with the result that loss of space is avoided as far as possible.

Finally, Figure 3 shows a cutting plate of the type having a central re-entrant portion 12 of rigid construction. Such a cutting plate is consequently provided with slots opening out in the re-entrant portion and extending towards the outer edge of the cutting plate, in the present case radially. The bulging and reinforcing ribs 4 according to the invention are arranged according to the central lines 13 at an angle of 120° relative to each other. Obviously, more than three bulging ribs may be provided and in this case their thickness may be smaller. From the viewpoint of symmetry less than two bulging ribs are not preferable in this case.

Generally, a thickness of the reinforcement ribs of approximately from 0.2 to 0.8 mm. suffices to bring about the desired effect; the spacing between the ribs also playing a part in this case.

In the case of circular shaving plates as shown

in Figures 1 and 3 it is preferable to cause the thickness to decrease according as the spacing between the bulging ribs decreases, as is otherwise shown in the figures.

5 What I claim is:

1. Dry shaving apparatus, comprising a substantially flat cutting plate with an enclosed cutting member, said cutting plate being provided with an apertured running surface for said member and comprising a plurality of sloping ribbed portions extending from the shaving surface thereof, said ribbed portions being integral with said cutting plate and so extending beyond the shaving surface of the said cutting plate to bulge the skin to be shaved.

2. Dry shaving apparatus, comprising an annular cup-shaped cutting plate and a cutting member, said cutting plate being provided with a central recess, having an annular apertured running surface and being provided with a plurality of sloped ridge portions radially extending from the said central recess from the shaving surface of said cutting plate, said ribbed portions being integral with said cutting plate and so extending beyond the shaving surface of the said cutting plate to flex the skin to be shaved.
